ELECTRIC CIRCUIT CONTROLLER

Chester Arthur Smith, Jr., Clifton Forge, Va.

Application April 11, 1946, Serial No. 661,241

1 Claim. (Cl. 173—324)

1

My present invention relates to an improved electric circuit controller and more particularly to a circuit controller for automobile ignition systems.

The principal object of my invention is to make it impossible to operate an automobile unless the speedometer is operating. It has been found, for instance, that taxicab operators sometimes disconnect the speedometer cable and drive unauthorized miles for personal reasons, or the speedometer cable may be detached and extra mileage added to the speedometer by manual rotation of the speedometer head.

By employing my invention in the ignition circuit of an automobile, between the ignition switch and the ignition coil, any tampering with the speedometer will break the circuit, and no current will be supplied to the engine.

In the accompanying drawings I have illustrated one complete example of the physical embodiment of my invention according to the best mode I have thus far devised but it will be understood that changes and alterations may be made in the exemplified structure within the scope of the appended claim without departing from the spirit of the invention.

In the drawings:

Figure 1 is a top plan view of one connector element.

Figure 2 is a transverse sectional view of the element of Figure 1 taken along line 2—2 of Figure 1.

Figure 3 is a top plan view of a second connector element.

Figure 4 is a transverse sectional view of the second element taken along line 4—4 of Figure 3.

Figure 5 is a diagrammatic view showing a portion of the automobile ignition circuit with the connectors therein.

Referring to the drawings, Figures 1 and 3 illustrate the two connector elements A and B forming the subject matter of the invention.

The element A is formed with a metal disk 1 having an insulating casing 2 cup-shaped and fashioned with a central opening 3 and an upturned flange 4. The casing is adapted to be attached to the speedometer housing in any conventional manner and is spaced therefrom by means of a washer 5. A bolt 6 is employed to secure the wire 7 to the disk and this wire is connected to the ignition switch (see Figure 5).

The inner face of the body or liner 1 is fashioned with spaced annular grooves 8 and 9 and an arcuate slot 10 is formed in the upper face of the disk between the grooves 8 and 9.

2

The element B as seen in Figures 3 and 4 comprises a ring 11 of insulating material substantially rectangular in cross-section and having raised, spaced, annular ribs 12 and 13 adapted for co-action with the annular grooves 8 and 9. At one point on the ring I have provided a ball contact 14 elevated above the plane of the ribs 12 and 13. The ball contact 14 is electrically connected to the ignition coil (see Figure 5) as by the wire 15 and is designed to co-act with the arcuate slot 10 on the disk 1 when the two elements A and B are associated.

Interior of the ring 11 I employ annular spaced retaining elements 16 and 17 forming an annular slot 18 therebetween. The slot 18 is designed to receive and maintain the H-shaped or slip ring 19 by means of the outer, annular flange 20. The ring 19 is also fashioned with an inner flange 21 adapted to be affixed to the coupling cup 22 of the speedometer cable 23.

In operation, the connector element A is fixedly secured to the speedometer housing and the ignition wire 7 is connected. The connector element B is fixedly secured on the speedometer cable cup, 25 and the ignition coil wire 15 is connected to the ring 11.

The cup is screwed upon the speedometer and the slip ring 19 provides relative rotary movement between the cup and the ring 11. When the cup is screwed home the grooves 8 and 9 will co-act with the ribs 12 and 13 and the ball connector will find the arcuate slot 10 and drop therein. The electric circuit as partially diagrammatically illustrated in Figure 5 will be complete so long as the two connectors A and B are not disturbed.

Any unloosening of the cable cup will break the circuit and the vehicle engine will not operate.

It will be apparent from the above description that the device of my invention will afford protection against unauthorized travel of the automobile in which the device is installed.

Having thus fully described my invention, what I claim as new and desire to secure by Letters Patent is:

In a connector for a speedometer cable having a coupling cup on the end thereof, the combination which comprises a ring H-shape in cross section having a continuous web with flanges at the edges said H-shaped ring being carried by the outer surface of the cup, a ring of insulating material rectangular-shape in cross section having an annular T-shaped groove in the inner surface slidably mounted on the flange on the outer edge of the said continuous web and hav-

ing spaced annular ribs on the face, a projection on said ring positioned between said annular ribs, and a complementary element having a disc-like liner of insulating material having annular grooves positioned to receive the said annular ribs of the said insulating ring, with an arcuate slot for receiving the said projection positioned between the said ribs and having an outer peripheral flange positioned to extend over the said ring of insulating material, said complementary element having a centrally disposed cable receiving opening therethrough.
